ATTORNEY

UNITED STATES PATENT OFFICE.

EDWIN YAWGER, OF EDGEWOOD PARK, PENNSYLVANIA, ASSIGNOR TO THE WESTINGHOUSE MACHINE COMPANY, A CORPORATION OF PENNSYLVANIA.

GAS-SCRUBBER.

968,307.

Specification of Letters Patent. Patented Aug. 23, 1910.

Application filed January 19, 1906. Serial No. 296,838.

To all whom it may concern:

Be it known that I, EDWIN YAWGER, a citizen of the United States, and a resident of Edgewood Park, in the county of Allegheny and State of Pennsylvania, have invented a new and useful Improvement in Gas-Scrubbers, of which the following is a specification.

This invention relates to gas scrubbers and has for an object the production of a centrifugal gas scrubber of simple construction that is effective and economical in operation.

A further object is the production of a gas scrubber that will effectively remove all solid material, dust, tar or tarry vapor that the gas may hold in suspension.

A further object is the production of a centrifugal scrubber from which the recrement material collected from the gas may be withdrawn without affecting the operation of the apparatus.

These and other objects I attain in an apparatus embodying the features herein described and illustrated.

In the single sheet drawing accompanying this application and forming a part thereof a vertical section of a scrubber embodying this invention is shown.

A rotor 2 is rigidly mounted on a vertical shaft 3 which is suitably journaled in the exterior casing 4 of the scrubber and is provided with an operating pulley 5. The rotor consists of a truncated cone-shaped hub portion 6 surrounded by an inclosing casing 7 which is supported on the hub by suitable webs 8.

The exterior casing 4 is provided with a gas inlet port 9 connected to a supply pipe 10, a water supply pipe 11 and a base portion 12 which consists of a water bottom adapted to seal the interior of the casing. A gas offtake passage 13 extends through the water bottom 12 and connects the interior of the casing with an offtake pipe 14, which communicates with a gas main or with other purifying apparatus.

The cylindrical wall 15 of the casing 4 extends downwardly into the water bottom of the base portion 12, which is provided with a water discharge pipe 16 arranged to maintain a definite amount of water in the base portion and thereby seal the lower edges of the wall 15, between which and the bottom of the base portion 12 an open-

ing 17 is maintained allowing access into the interior of the casing. The interior of the casing is divided into chambers 18 and 19 by a diaphragm or partition 21. The rotor 2 is located in the chamber 19 which connects with the water seal opening 17; the gas and water supply ports 9 and 11 respectively communicate with the chamber 18.

Inclosed between a circular wall 22 of the rotor casing 7 and the top surface of the hub portion 6 is a passage 23 which communicates with the chamber 18 through a circular opening 24. A chamber 25 of larger diameter than the chamber 23 is inclosed between the lower face of the hub portion 6 and a circular wall 26 of the casing 7. The chamber 25 communicates with the gas outlet passage 13 through a circular opening 27 and with the chamber 23 through an annular passage 28, which is inclosed between the conical wall of the hub portion 6 and the cylindrical portion of the casing 7 parallel to it.

An annular row of recrement discharge openings 29 in the rotor casing 7 open from the passage 28 into the chamber 19 which communicates with the chamber 18 through suitable openings 30 located in the partitions 21. The chamber 18 communicates with the chamber 23 of the rotor casing 7 through annularly arranged ports 31 and the circular opening 24.

The water entering the chamber 18, through the pipe 11, is collected by an integrally formed ring 32 of the partition 21 and is discharged into the chamber 23 through the gas inlet ports 31.

The operation of the apparatus is as follows: The rotor 2 is rotated at a suitable speed and gas is admitted through the port 9 to the chamber 18, and in passing therethrough is wet and cooled by the water entering the chamber through the pipe 11. The gas and water enter the rotor passages through the annularly arranged ports 31 and the circular opening 24.

The gas on entering the rotor passages is subjected to the centrifugal force occasioned by the rotation, but because of the rotor's construction, that is, the arrangement of the webs 8, there is little or no relative rotary motion between it, the said gas, and the rotor.

The water in entering the passage 23, through the opening 24, is thrown out

wardly by the centrifugal force and is distributed throughout the passages 23 and 28 by the rotary motion, thereby wetting the surfaces of the passages and the webs 8.

5 The gas entering the passage 23, from the chamber 18, comes into intimate contact with the wet surfaces of the passage and the webs 8, and the dust and particles of tarry material mechanically entrained are either 10 collected by the wet surfaces or projected by their acquired centrifugal force against the inclined sides of the passage 28.

The gas in leaving the passage 23 turns almost at right angles on entering the passage 28; this arrangement aids the operation of scrubbing the gas as the recrement articles, because of their weight, or more properly their inertia, resist the sharp turn and lodge on the outer wall of the passage 20 28, which is wet by a continuous flow of water discharged from the passage 23. Since the passage 28 is cone-shaped, the scrubbing action of the centrifugal force on the gas increases as the gas passes there- 25 through and the refuse material and cleansing water is impelled along the inclined walls of the passage by the combined action of gravity and a component of the centrifugal force, and is discharged from the rotor 30 through the discharge ports 29, which are located at the bottom of the passage in the zone of the greatest centrifugal action.

The gas in leaving the passage 28 and entering the passage 25 is turned through an acute angle and impelled in a direction directly opposite to the action of the centrifugal force; the dust, tar and particles of moisture that the gas may carry are therefore checked by the centrifugal force and 40 dropping to the bottom of the passage 25 are discharged through the recrement ports 29.

The recrement and the water discharged from the ports 29 drop into the water bottom 45 12, from which the recrement may be drawn through the water sealed opening 17 without interfering with the operation of the apparatus.

The gas discharged from the rotor passages through the ports 29 into the chamber 19 returns to the chamber 18 through the ports 30, and with this arrangement the tendency of the gas to leak through the joints between the rotor and the stationary 55 casing, and thereby escape the scrubbing action, is overcome.

The webs 8 may be rearwardly inclined with reference to the motion of the rotor, thereby facilitating the flow of gas through 60 the passage, and to some extent compensating the velocity losses due to the friction which the inertia of the gas occasions in causing the gas to lag behind the rotor.

The gas may be propelled through the 65 scrubber by a rotary or any other form of

fluid propelling agent located either within or exterior to the exterior casing; and while I have described but one form of my invention it is evident that other forms and arrangements may be resorted to and still fall within the limits and scope of my invention.

What I claim and desire to secure by Letters Patent is:

1. A gas purifier comprising a rotatable element provided with an interior passage for impure gas, means for introducing water to said passage, means for progressively increasing the action of centrifugal force upon the recrement material separated from said gas and water in said passage, a gas admission port, a gas exhaust port, and means for scrubbing the gas passing through said passage, in combination with an inclosing passage provided with a gas inlet port, a gas outlet port, a recrement discharge port, and a water seal for said recrement discharge port. 75 80 85

2. A gas purifier comprising a rotatable element provided with interior gas passages, means for introducing water to said passages, means for progressively increasing the action of centrifugal force upon the recrement material separated from said gas and water in said passage, a gas admission port, a gas exhaust port, means for scrubbing the 95 gas passing through said passages and ports for discharging the recrement from said passages and an inclosing casing for said element provided with a gas inlet port, a gas outlet port, and a water sealed recrement 100 discharge port. 90

3. A gas purifier comprising a rotatable element provided with a gas scrubbing passage, means for introducing water to said passage, means for progressively increasing the action of centrifugal force upon the recrement material separated from said gas and water in said passage, a gas admission port, a gas exhaust port, and a recrement discharge port 105 communicating with said passage, and means for scrubbing the gas passing through said passage, in combination with an inclosing casing for said element which is provided with a gas admission chamber communicating with a gas admission port of 110 said element and a recrement discharge chamber communicating with the recrement discharge of said element and provided with a water sealed recrement discharge port. 115

4. A gas purifier, a rotatable element provided with interior gas passages, means for introducing water to said passages, means for progressively increasing the action of centrifugal force upon the recrement material separated from said gas and water in 125 said passages, a gas admission port, a gas exhaust port, recrement discharge ports communicating with said passages, and means for scrubbing the gas passing there- 130 through, in combination with a stationary

- casing for said element provided with a gas delivery chamber communicating with the inlet port of said element, a recrement delivery chamber communicating with the recrement delivery port of said element, a source of water supply located within said gas delivery chamber and a pressure equalizing passage between said admission chamber and said recrement chamber.
5. A gas purifier comprising a rotatable element provided with an annular gas passage, means for introducing water to said passage, means for progressively increasing the action of centrifugal force upon the recrement material separated from said gas and water in said passage, a gas admission port, a gas exhaust port and recrement discharge ports communicating with said passage, and means within said passage for scrubbing the 10 gas and for facilitating the flow of gas therethrough, in combination with an inclosing casing for said element divided into a gas admission chamber through which the gas is delivered and which communicates 15 with the gas inlet port of said element, and
- a gas delivery port which communicates with the recrement discharge ports of said element and is provided with a water sealed recrement discharge port and a gas delivery port which communicates directly with the 20 gas delivery port of said element.
6. In a gas purifier, an outer casing and an inner casing, a shaft for the inner casing provided with a hub symmetrical with the inner casing, an inlet port at the top of the 25 inner casing to admit gas and water, a gas outlet port for the inner casing, water sealed recrement discharge openings for the inner casing, and a gas outlet space between the inner and outer casing whereby gas may 30 pass from the recrement discharge opening back through the inlet port at the top of the inner casing.
- In testimony whereof, I have hereunto subscribed my name this 17th day of January, 1906.
